[57] CLAIM

The ornamental design for an aqua planing board, substantially as shown and described.

DESCRIPTION

FIG. 1 is a perspective view of my new and ornamental design for an aqua planing board;

FIG. 2 is a top plan view thereof;

FIG. 3 is a side elevational view thereof;

FIG. 4 is a rear elevational view thereof;

FIG. 5 is a front elevational view thereof;

FIG. 6 is a bottom plan view thereof;

FIG. 7 is a cross-sectional view taken on the plane designated by line 7—7 of FIG. 6; and

FIGS. 8, 9 and 10 are cross-sectional views taken on the planes designated by lines 8—8, 9—9 and 10—10 of FIG. 7.

FIG. 1.

FIG. 2.

FIG. 3.

FIG. 4.

FIG. 5.

FIG. 6.

FIG. 7.

FIG. 8.

FIG. 9.

FIG. 10.
